CRAYON SHARPENER

Oscar L. Gerwig, Pittsburgh, Pa.

Application October 25, 1940, Serial No. 362,706

4 Claims. (Cl. 120—96)

This invention relates to improvements in crayon sharpeners and more particularly to a sharpener for crayons of substantially rectangular cross section and made out of talcum or other similar material. Such crayons are used by layout men in structural steel plants, boiler shops and many others.

As is well known, crayons for the above mentioned purpose are marketed in the form of sticks $\frac{1}{2}$ inch wide by $\frac{1}{8}$ inch thick and about 5 inches long and they must be sharpened by the user to a fine tapered edge along the full width of the crayon. Heretofore this was accomplished by sharpening the crayons by hand on an abrasive surface, such as sand or emery paper, a file or other abrasive materials and since the crayons are made of talcum, an extremely soft material, it was very difficult to produce a long tapered sharp edge without breaking the same.

It is therefore one of the main objects of this invention to produce a crayon sharpener which sharpens crayons to a long tapered edge with a minimum susceptibility to breakage.

Another object of the invention is to provide a crayon sharpener which will produce a perfectly smooth and straight edge.

Still another object of the invention is to provide a crayon sharpener in which the abrasive material is not secured to or part of the rotatable discs.

Yet another object of the invention is to provide a crayon sharpener with abrasive discs which may be renewed without completely taking the device apart.

Another object of the invention is to provide an extremely simple and substantial crayon sharpener which requires a reduced number of parts and a minimum of maintenance care and which is at the same time of enhanced efficiency and serviceability.

Further objects, and objects relating to details and economies of construction and operation will definitely appear from the detailed description to follow.

In the accompanying drawings forming a part of this application, and in which similar reference symbols indicate corresponding parts in the several views,

Figure 1 is a side view of the complete device.

Figure 2 is a top view of Figure 1 with part of the cover removed.

Figure 3 is an end view of Figure 1 with part of the cover removed.

Figure 4 is a central cross-section of the device on line 4—4 in Figure 1 showing the shaft re-

moved and one of the discs moved sidewise in the direction of the arrow.

Figure 5 is a view similar to Figure 3 showing one of the crayons inserted between the abrasive discs and sharpened to a taper edge.

Figure 6 illustrates the shaft as used in this invention.

Figure 7 shows one of the crayons having a single tapered edge.

Figure 8 shows a crayon having a double taper edge.

Figure 9 is an end view of Figure 7 or 8.

Figure 10 is a top view of the guide as used in this invention.

Figure 11 shows a developed view of the guide shown in Figure 10, before bending on dot and dash lines.

Referring to the drawings in detail, and particularly to Figures 1 to 5 inclusive, the numeral 20 indicates a casing which may be conveniently made of sheet metal or formed by die casting or otherwise. The casing 20 comprises two side members 21, a top member 22 and an end-bracket 23 which is provided with screw or bolt holes 24 for the reception of screws or bolts (not shown) by means of which the casing 20 may be mounted on a wall or desk or any other suitable place.

Referring now to Figure 4 in which is shown a sectional view of the device with the shaft 25, which is shown detailed in Figure 6, removed. The side members 21 of said casing 20 are provided with horizontally aligned bearing bushings 26 welded to the inside face 27 and outside face 28 of said side members 21, as shown, in which are rotatably mounted the sleeves 29, one in each pair of bearing bushings 26. Each of said sleeves 29 is provided with a properly spaced circular flange 30, dividing the former into the disc carrying end 31 and the bearing end 32.

The discs 33 and 34, of wood, sheet metal or any other suitable material are provided with a central aperture 35 which snugly fits over the end 31 of said sleeves 29 and said discs are prevented from turning on said ends 31 by means of a screw through the side face of the flange 30, or otherwise. The opposing inner faces 37, 38 of the discs 33, 34 respectively are beveled to a taper corresponding to the taper 39 of the guide 40, which, by the way, determines the taper of the sharpened crayon 41, shown in Figures 8 and 9.

The disc 34, at the operating handle end is held from side-wise movement by the operating handle 42 which is attached to the bearing end 32 of said sleeve 29 by a set screw 43, or otherwise.

The disc 33, including the sleeve 29 on which the former is securely mounted, is slidably mounted in the bearing bushings 26, in order to permit the said disc to be moved outwardly in direction of arrow shown in Figure 4 when it is desired to replace the abrasive discs 44. It will be noted, that said abrasive discs 44 lay loosely between the discs 34 and 33 and are centrally supported by the shaft 25 which is shown detailed in Figure 6 of the drawings. The aforesaid shaft 25 comprises a rod 45 having securely attached at one end thereof a washer 46 while the other end is threaded as at 47 adapted to receive a wing nut 48.

Secured to the underside 49 of said top 22 of the casing 20 is a guide 40, detailed in Figures 3, 10 and 11, which may be of steel plate or other desirable material. This guide is shown as made in one piece in the shape of a U and bent along the dot and dash lines to form an angle of about ninety degrees, as best shown in Figure 3. The prongs 50 are tapered, as at 39, at an angle to conform with the bevel 51 of said discs 33 and 34, which corresponds to the desired taper of the sharpened crayon 41.

The top 22 of said casing 20 is provided with a rectangular opening 52, preferably of the size of the crayon, through which the latter may be inserted for sharpening.

The open lower end 53 of said casing 20 may be closed up by means of a detachable cover 54 where talcum dust and dirt may be collected to be later removed at intervals.

From the foregoing description of the parts used in this device the operation of the same will be very readily understood.

Assuming that the shaft 25 is inserted through the bearing bushings 26 with the washer 46 at the operating handle end and locked by the wing-nut 48. By doing this, the discs 33 and 34 are then so placed together that a V shaped space 55 is left between their peripheries which corresponds to the V shaped taper 39 of said guide 40. At this time attention is called to the fact that the abrasive discs 44 are not dished to conform to the bevel of the discs 33 and 34 but they are perfectly flat before inserting and moreover they are not cemented or otherwise secured to the discs. This fact is very important when considering the cost to produce abrasive discs 44 and also considering the time it consumes for cleaning or replacement.

Bearing in mind that talcum crayons are very soft, the abrasive discs should be cleaned often with a suitable brush or other similar means.

In operation, it is only necessary to insert a crayon 41 through the rectangular opening 52 and between the depending prongs 50 of guide 40. The operating crank or handle 42 is then turned which provides circular movement to the discs 33 and 34, and since the abrasive discs 44 are pinched together at the central flat inner face 56 of said discs 33 and 34 the same will also receive circular movement. The crayon is slowly fed by the user and the sides of the same are consequently ground away by the abrasive surfaces of the abrasive discs 44.

The cover 54 is removed when it is desired to empty the talcum dust collected and also when it is desired to clean the abrasive surfaces of the abrasive discs or to renew the same.

The said abrasive discs are cleaned or renewed by first removing the cover 54, unscrewing the wing-nut 48 from shaft 25. By removing said shaft 25, disc 33 may be moved outwardly after which the abrasive discs may be withdrawn.

After the abrasive discs have been cleaned or renewed the shaft 25 is again inserted as heretofore described and again locked by the wing-nut 48. The cover 54 may then be replaced by inserting the cover hook-end 57 into the casing hook-end 58 and snapping the same into position by the latch 59.

In Figure 7 there is shown a crayon which has only one side tapered, in this case, one of the abrasive discs 44 may be eliminated to obtain the desired result.

From the foregoing description taken in connection with the accompanying drawings, the construction of the device and the method of operation will be readily apparent to those skilled in the art to which the invention appertains, and while describing the principle of operation of the invention together with the device which is now considered to be the best embodiment thereof, it is to be understood the various changes in the form, proportion and the minor details of construction may be resorted to without sacrificing any of the advantages of the invention as defined in the appended claims.

25 I claim:

1. A crayon sharpener of the kind described comprising a casing provided with a pair of aligned bearing bushings; a pair of circular discs, each provided with a centrally disposed and outwardly extending sleeve adapted to rotate in one of said bearing bushings, said circular discs also provided with a frusto-conical inner face; a tie-rod extending through said sleeves loosely supporting a pair of opposing abrasive discs; means to tighten said tie-rod and means to simultaneously rotate all of said discs.

40 2. A crayon sharpener of the kind described comprising a casing provided with a pair of aligned bearing bushings; a pair of circular discs, each provided with a centrally disposed and outwardly extending sleeve adapted to rotate in one of said bearing bushings, said circular discs also provided with a frusto-conical inner face; one of said circular discs arranged for rotary motion and axial movement and the other one mounted for rotary motion only; a tie-rod extending through said sleeves loosely supporting a pair of opposing abrasive discs; means to tighten said tie-rod and means to simultaneously rotate all of said discs.

45 3. A crayon sharpener of the kind described comprising a casing provided with a pair of aligned bearing bushings; a pair of circular discs, each provided with a centrally disposed and outwardly extending sleeve adapted to rotate in one of said bearing bushings, said circular discs also provided with a frusto-conical inner face; one of said circular discs arranged for rotary motion and axial movement and the other one mounted for rotary motion only; a tie-rod extending through said sleeves loosely supporting a pair of opposing abrasive discs; means to tighten said tie-rod thereby causing all of said discs to form a single operating member and means for rotating the latter.

50 4. A crayon sharpener of the kind described comprising a casing provided with a pair of aligned bearing bushings, each adapted to rotatably receive a circular disc having frustum-shaped inner faces; one of said discs arranged for rotary motion and axial movement and the other one for rotary motion only; the frusto-conical inner faces of said circular discs, when in operable position, providing a V-shaped space between their peripheral edges; a tie-rod extend-

ing through said circular discs loosely supporting a pair of opposing abrasive discs, each having an unsupported peripheral portion; means to tighten said tie-rod thereby causing all of said discs to be held together in frictional engagement to form a single rotatable operating member; a stationary bifurcated V-shaped guide inserted between said

abrasive discs adapted to urge said unsupported peripheral portion of the latter against the frusto-conical inner faces of said circular discs; an opening in said housing to permit a crayon to be inserted between said bifurcated guide and means to simultaneously rotate all of said discs.

OSCAR L. GERWIG.
